CLAIM

The ornamental design for an LED matrix display as shown and described.

DESCRIPTION

FIG. 1 is a front perspective view of an LED matrix display according to the first embodiment of the present disclosure.

FIG. 2 is a front elevation view thereof.

FIG. 3 is a rear elevation view thereof.

FIG. 4 is a first side view thereof.

FIG. 5 is a second side view thereof.

FIG. 6 is a top plan view thereof.

FIG. 7 is a front elevation view thereof illustrating the LED matrix display in a gaming environment.

FIG. 8 is a front perspective view of an LED matrix display according to the second embodiment of the present disclosure.

FIG. 9 is a front elevation view thereof.

FIG. 10 is a rear elevation view thereof.

FIG. 11 is a first side view thereof.

FIG. 12 is a second side view thereof.

FIG. 13 is a top plan view thereof.

FIG. 14 is a front elevation view thereof illustrating the LED matrix display in a gaming environment.

FIG. 15 is a front perspective view of an LED matrix display according to the third embodiment of the present disclosure.

FIG. 16 is a front elevation view thereof.

FIG. 17 is a rear elevation view thereof.

FIG. 18 is a first side view thereof.

FIG. 19 is a second side view thereof.

FIG. 20 is a top plan view thereof; and,

FIG. 21 is a front elevation view thereof illustrating the LED matrix display in a gaming environment.

(Continued)

The shade lines in the Figures show contour and not surface ornamentation. The broken lines in the Figures show portions of the support structure and its surrounding environment that form no part of the claimed design.
